(57) **CLAIM**

The ornamental design for a control handle for an endoscopic device, as shown and described.

DESCRIPTION

FIG. 1 is a perspective view of an embodiment of a control handle for an endoscopic device;

FIG. 2 is a rear elevational view of the embodiment of FIG. 1; FIG. 3 is a front elevational view of the embodiment of FIG. 1;

FIG. 4 is a right side elevational view of the embodiment of FIG. 1;

FIG. 5 is a left side elevational view of the embodiment of FIG. 1;

FIG. 6 is a top plan view of the embodiment of FIG. 1; and, FIG. 7 is a bottom plan view of the embodiment of FIG. 1.

The portion of the article shown in broken lines in FIGS. 1–7 is for illustrative purposes only and forms no part of the claimed design.
